ARTIFICIAL LIMB

Argiel W. Rogers, Long Beach, Calif.

Application April 25, 1945, Serial No. 590,141

5 Claims. (Cl. 3-2)

1

This invention relates to artificial limbs and particularly to artificial legs and has for an object to provide a more natural and more comfortable limb than any I have been able to find.

Another object of the invention is to provide an artificial leg only one comparatively inexpensive member of which has to be renewed upon shrinkage of the stump of the natural limb which reoccurs ever so often.

Another object of the invention is to provide in an artificial leg means for nice adjustment relative to the user thereof.

A further object of the invention is to provide in an artificial leg means whereby when in sitting position the foot sole of the foot may rest flat upon the floor, thus lending a more natural appearance to the leg.

Another object of the invention is to provide in an artificial leg means whereby the leg may be caused to pivot toward the toe of the foot in order that the user may easily assume a squatting position.

A still further object of the invention is to provide such clearance between the upper portion of the leg and its boot whereby free knee action is permitted and adjustments may more readily be made.

Another object is to so construct the femoro stump receiving socket member as to reduce its original and replacement costs, provide a reduced diameter thereof so as not to be noticed with the trouser leg and yet be strong and durable.

Other features and advantages will become more readily apparent from the following description and the accompanying illustrative drawings in which:

Figure 1 is a side elevational view of my improved leg, different positions thereof relative to the foot being shown in dotted lines,

Figure 2 is a sectional elevational view of the leg,

Figure 3 is a sectional view taken on line 3-3 of Figure 2,

Figure 4 is a section taken on line 4-4 of Figure 2, parts being removed,

Figure 5 is a top plan view, partly in section, looking into the leg, and

Figure 6 is a section on line 6-6 of Figure 5.

In the following specification as well as in the above illustrated drawings, like reference characters designate like parts in which 10 is my improved limb including the socket member 11, leg portion 12, and foot 13. The member 11 is formed of a leather cup or socket 14, into which the femoro stump of wearer's limb seats. This

cup is wrapped with copper wire 15, around which is applied a coating of solder 16, which is just heavy enough to form a strong support for the stump yet by far not so bulky as an all leather cup, the walls of which must be very thick in order to stand up under the weight placed thereon. The bottom of my cup member 11 is provided with a bottom disk 17, to which is bolted a metal cap plate 18, by means of bolts 19, which cap is the head of a tubular tibia or shin member 20, the lower end 21 of which is somewhat flattened in and is provided with a transverse bore which projects down into the pocket 22, formed in a block 23, which is seated upon a rubber cushion 24. Both of the members 23 and 24 are secured within the cavity 25, in heel portion 26, of the foot 13, by means of a U-bolt 27, the arms 28 and 29 of which project through the bottom wall 30 of said foot. The head 31, of said bolt 27, passes through a longitudinal horizontally disposed bore 32, in the center of the block 23, and forms a slight pivoting means for the block, which is limited by the clearance between the side walls 33 and 34, of the cavity 25 and the action of cushion 24, but which is sufficient to permit sidewise bending of the foot, which will avoid shocks in certain instances, which otherwise would be transmitted to the wearer's stump. This sidewise movement also tends to lend naturalness in walking.

The said end 21 of member 20 is secured within said pocket 22, by means of a pivot pin 35, passing through transverse bores 36 and 37, in the block 23, and through the above referred to bore in said end 21.

Secured to the member 20, by the terminals 38, 39, 40, etc., are U-bolts 41 and 42, the heads 43 and 44, of which pass through a block 45, to which block is secured tubes 46 and 47, to which are adjustably supported screw-threaded rods 48 and 49. The lower end 50, of member 48, projects down into the pocket 22, and is secured therein by means of a pin 51, to which it is welded. The member 48, is substantially a substitute for the fibula of the human leg. The block 45, which is of a suitable rigid material, has front and back plates 52 and 53, secured thereto by bolts 54 and 55, and through an aperture 56, in plate 52, and an aligning recess 57, in block 45, the end 58, of a pin 59, is adapted to seat. Said pin passes slidably through bores 60 and 61, in the front and back walls of member 20. The position of the pin 59, when in its locking position permits only a slight pivotal movement of member 20, limited by the vertical length of

the slot 60, which allows just sufficient movement for walking. However, in order to assume a sitting or squatting position, such as indicated in dotted lines 61 and 62, of Figure 1, pin 59, may be withdrawn from engagement with the member 45, by means of a leaf spring 63, through which the head 64, of said pin 59, passes, thus freeing member 45, to slide up or down upon the said U-heads 43 and 44, and also permitting free pivotal movement of member 20, either forward or backward.

The lower end 65, of spring 63, has a right angular projection 66, which bears upon the member 20, and its upper end 67, is normally pressed forward by a spring 68, whereby the pin 59, is normally held in locking position relative to member 45. However, to the extreme upper end 69, of spring 63, is secured the end 70, of a strap 71, which is adjustably attached to a staple 71', through means of a buckle 71'', with just sufficient slack to permit of free walking movement; however, by throwing the leg back to take up the slack spring 63, is drawn against the tension of coil spring 68, drawing out pin 59, and releasing block 45, to permit free movement of the leg back or forward as indicated at 61 and 62, of Figure 1.

The members 48, 49 and 28, are adjustable through means of the nuts 72, 73, 74 and 75. A shell 76, encases the tibia and fibula members 20 and 45, and connections and is so shaped at its bottom edge 77, as to have the free movement relative to the foot 13, as indicated in Figure 1 of the drawings. The tube 46, is formed of rubber or other such element which will permit of sufficient movement between tibia and fibula members for ease in walking and give natural springiness to the movement of the leg. To the instep portion 78, of the foot 13, is secured a toe end 79, formed of rubber, by means of its tongue 80, seating in a groove 81, in said portion 78, and held by pins 82.

From the foregoing it will be obvious that upon such shrinking of the user's stump it would be necessary to replace a new cup properly fitted, instead of an entire new leg.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

Having now described my invention that which I claim as new and desire to procure by Letters Patent is:

1. An artificial leg including a stump cup, a leg section and a foot, said cup being spaced from the leg portion, a tubular tibia member forming the spacing means, said member having transverse pivotal connection with the foot, a fibula member having slidable connection with the tibia

member and normally limited pivotal connection with the foot, means whereby the fibula member may limit movement of the tibia member, said means being a spring actuated lock pin and automatic means for releasing the pin, said cup comprising a leather lining, a wrapping of wire there-around and a lead coating formed on the wire.

2. An artificial leg including a stump cup, a leg section and a foot, said cup being spaced from the leg portion, a tubular tibia member forming the spacing means, said member having transverse pivotal connection with the foot, a fibula member having slidable connection with the tibia member and normally limited pivotal connection with the foot, means whereby the fibula member may limit movement of the tibia member, said means being a spring actuated lock pin and automatic means for releasing the pin.

3. An artificial leg including a stump cup, a leg section and a foot, said cup being spaced from the leg portion, a tubular tibia member forming the spacing means, said member having transverse pivotal connection with the foot, a fibula member having slidable connection with the tibia member and normally limited pivotal connection with the foot, and means whereby the fibula member may limit movement of the tibia member, said means being a spring actuated lock pin.

4. An artificial leg including a stump cup, a section and a foot, said cup being spaced above the leg portion, a tubular tibia member forming the spacing means, said member having transverse pivotal connection with the foot, a fibula member having slidable connection with the tibia member and normally limited pivotal connection with the foot, and resiliently biased means for limiting movement of the tibia member.

5. An artificial leg comprising a stump cup, a leg section, a tibia member secured to said stump cup and spacing said cup and leg sections, a foot portion pivotally secured to said tibia member, a resilient means interposed between said foot portion and said tibia, a fibula pivoted to said foot portion and slidably secured to said tibia member, means for limiting the movement of the tibia member, said last means including a resiliently biased locking pin and means for releasing said pin.
